US00D976109S

(12) **United States Design Patent** (10) **Patent No.:** **US D976,109 S**
(45) **Date of Patent:** **** Jan. 24, 2023**

(54) **BOTTLE**

(71) Applicant: **THE CLOROX COMPANY**, Oakland, CA (US)

(72) Inventors: **Hyun Jin Ko**, Pleasanton, CA (US); **Mark D. Pszczołkowski**, Pleasanton, CA (US); **Kerry D. Azelton**, Pleasanton, CA (US); **Alea L. Reidinger**, Pleasanton, CA (US); **Scot Herbst**, Santa Cruz, CA (US); **William W. Hunter**, Denver, CO (US); **Elisabeth Morris**, Santa Cruz, CA (US)

(73) Assignee: **THE CLOROX COMPANY**, Oakland, CA (US)

(**) Term: **15 Years**

(21) Appl. No.: **29/784,801**

(22) Filed: **May 21, 2021**

(51) **LOC (14) Cl.** **09-03**

(52) **U.S. Cl.**

USPC **D9/500**

(57) **CLAIM**

The ornamental design for a bottle, as shown and described.

DESCRIPTION

FIG. 1 is a perspective view of a bottle, showing our new design;

FIG. 2 is a right side view thereof;

FIG. 3 is a left side view thereof;

FIG. 4 is a front view thereof;

FIG. 5 is a rear view thereof; and,

FIG. 6 is a top view thereof.

The broken lines in the drawings depict portions of the bottle that form no part of the claimed design.

1 Claim, 6 Drawing Sheets
